UNITED STATES PATENT OFFICE.

WILLIAM E. ARNOLD, OF ROCHESTER, NEW YORK, ASSIGNOR TO WILMOT CASTLE, OF SAME PLACE.

BOILER FOR COOKING GRAIN.

SPECIFICATION forming part of Letters Patent No. 257,810, dated May 9, 1882.

Application filed February 1, 1882. (No model.)

To all whom it may concern:

Be it known that I, WILLIAM E. ARNOLD, of Rochester, Monroe county, New York, have invented a certain new and useful Improvement in Boilers for Cooking Grains and Farinaceous Food; and I do hereby declare that the following is a full, clear, and exact description of the same, reference being had to the accompanying drawings, in which—

Figure 1 is a central vertical section of the apparatus. Fig. 2 is a cross-section in line *xx*.

My invention relates to boilers for culinary and domestic use, and is an improvement upon the apparatus patented by me July 8, 1879.

The invention consists in the construction and arrangement of parts hereinafter more fully described and definitely claimed.

In the drawings, A shows the boiler, and B the kettle or cooker. The boiler is open-topped, and the kettle, which sits therein and contains the material to be cooked, is closed by a cover, *a*, and may be made of any desired form, but preferably dish-shaped, as shown. The upper portion of the boiler is also conical, and a jacket-space, *b*, is left between the two parts, which gradually contracts to nothing at the top.

C is the supply-reservoir for containing water, the same being pan-shaped, and located outside of the boiler.

D is a heating-reservoir, consisting of a very thin vessel, which rests over the fire and receives the direct action of the heat. It receives its supply of water from the supply-reservoir through small holes or passages *c c c*, formed in depressions *H H* of the reservoir, which rest upon and form bearings with the top of the heating-reservoir. The heating-reservoir D communicates directly with the bottom of the boiler by a central tubular passage, F, which really forms a continuation of the boiler, the water rising in said tubular passage on a level with that in the supply-reservoir. The water in the thin heating-reservoir becomes rapidly heated, and, rising in the tubular passage, is converted into steam, which rises in the jacket-space *b* and surrounds the cooking-receptacle. As fast as the water is evaporated its place is supplied by water from the supply-reservoir.

E is a cylindrical casing or jacket, which surrounds the water-passage F, leaving an air-space, *g*, between them, which communicates at the bottom with the air-passage *h* between the supply and heating reservoirs. The air entering and passing through these spaces escapes at the top through holes *i i*, thus insuring a constant circulation, and keeping the cool water in the supply-reservoir from coming in contact with and cooling the water in the boiler, or the water in the boiler heating the supply-water.

K is a condenser, consisting of a top cover, *k*, and a cylindrical open-ended body, *l*, which rests over and incloses the body of the boiler and kettle, as shown in Fig. 1. The open lower end comes nearly to the level of the bottom of the boiler, thus forming a jacket-space, *m*, opposite the inside jacket-space, *b*, and this open end rests directly above the supply-reservoir, so that the water of condensation gathered by the condenser will drip back into the reservoir, and can be used over again and again. The top of the condenser rests upon an open-sided boss, *r*, formed on top of the cover *a*, by which the condenser is properly supported, and a space is also left between the cover and the condenser for the steam.

The operation will be understood. The steam passing up the jacket-space *b* surrounds the sides of the cooking-vessel as well as the bottom. Escaping past the cover, the steam also surrounds the top, being retained by the condenser. As fast as the water is condensed it drips back into the supply-reservoir. The condenser, being simply an inverted cover, is readily applied or removed. The steam which escapes from the boiler into the condenser not only surrounds the top, but also the sides of the boiler and kettle, thereby equalizing and increasing the heat.

Having thus described my invention, I claim—

1. In a cooking-boiler, the combination, with the boiler A and supply-reservoir C, of the condenser K, covering the boiler, and having an open bottom which rests over the supply-reservoir, as and for the purpose specified.

2. In a cooking-boiler, the combination of the supply-reservoir C, the heating-reservoir

- D, the tubular water-passage F, the casing E, the boiler A, the kettle B, and the condenser K, as shown and described, and for the purpose specified.
5. In a cooking-boiler, the combination, with the supply-reservoir C and heating-reservoir D, of the central tubular water-passage, F, forming the intermediate portion of the boiler, and the exterior casing, E, leaving a flue-space 10 between itself and the water-passage, and provided at its top with holes *i i*, as shown and described, and for the purpose specified.
4. In a cooking-boiler, the combination of the heating-reservoir D, the tube F, and casing E, forming a flue, the boiler A, the kettle B, the cover *a*, having the projecting boss *r*, 15 and the condenser K, substantially as specified.
5. In a cooking-boiler, the combination, with the supply-reservoir C, of the double-walled flue, consisting of the tube F and casing E, 20 with holes *i i* at the top of the casing and holes or passages *c c* leading from the supply-reservoir to the heating-reservoir beneath the tube F, as herein shown and described.
- In witness whereof I have hereunto signed 25
name in the presence of two subscribing witnesses.

WILLIAM E. ARNOLD.
